(57) **CLAIM**

An ornamental design for a salad shaker bowl with exchangeable inserts, as shown and described.

DESCRIPTION

FIG. 1 is a perspective view of a bowl of a salad shaker bowl, in accordance with the present design.

FIG. 2 is a front view of the bowl of the salad shaker bowl of FIG. 1, in accordance with the present design.

FIG. 3 is a rear view of the bowl of the salad shaker bowl of FIG. 1, in accordance with the present design.

FIG. 4 is a left side view of the bowl of the salad shaker bowl of FIG. 1, in accordance with the present design.

FIG. 5 is a right side view of the bowl of the salad shaker bowl of FIG. 1, in accordance with the present design.

FIG. 6 is a top view of the bowl of the salad shaker bowl of FIG. 1, in accordance with the present design.

FIG. 7 is a bottom view of the bowl of the salad shaker bowl of FIG. 1, in accordance with the present design.

FIG. 8 is a perspective view of a first insert of the salad shaker bowl of FIG. 1, in accordance with the present design.

FIG. 9 is a front view of the first insert of the salad shaker bowl of FIG. 1, in accordance with the present design.

FIG. 10 is a rear view of the first insert of the salad shaker bowl of FIG. 1, in accordance with the present design.

FIG. 11 is a left side view of the first insert of the salad shaker bowl of FIG. 1, in accordance with the present design.

FIG. 12 is a right side view of the first insert of the salad shaker bowl of FIG. 1, in accordance with the present design.

FIG. 13 is a top view of the first insert of the salad shaker bowl of FIG. 1, in accordance with the present design.

FIG. 14 is a bottom view of the first insert of the salad shaker bowl of FIG. 1, in accordance with the present design.

FIG. 15 is a perspective view of an assembly of the bowl of the salad shaker bowl of FIG. 1 and the first insert, in accordance with the present design.

FIG. 16 is a perspective view of a second insert of the salad shaker bowl of FIG. 1, in accordance with the present design.

FIG. 17 is a front view of the second insert of the salad shaker bowl of FIG. 1, in accordance with the present design.

FIG. 18 is a rear view of the second insert of the salad shaker bowl of FIG. 1, in accordance with the present design.

FIG. 19 is a left side view of the second insert of the salad shaker bowl of FIG. 1, in accordance with the present design.

(Continued)

FIG. 20 is a right side view of the second insert of the salad shaker bowl of FIG. 1, in accordance with the present design.

FIG. 21 is a top view of the second insert of the salad shaker bowl of FIG. 1, in accordance with the present design.

FIG. 22 is a bottom view of the second insert of the salad shaker bowl of FIG. 1, in accordance with the present design.

FIG. 23 is a perspective view of an assembly of the bowl of the salad shaker bowl of FIG. 1 and the second insert, in accordance with the present design.

FIG. 24 is a perspective view of a third insert of the salad shaker bowl of FIG. 1, in accordance with the present design.

FIG. 25 is a front view of the third insert of the salad shaker bowl of FIG. 1, in accordance with the present design.

FIG. 26 is a rear view of the third insert of the salad shaker bowl of FIG. 1, in accordance with the present design.

FIG. 27 is a left side view of the third insert of the salad shaker bowl of FIG. 1, in accordance with the present design.

FIG. 28 is a right side view of the third insert of the salad shaker bowl of FIG. 1, in accordance with the present design.

FIG. 29 is a top view of the third insert of the salad shaker bowl of FIG. 1, in accordance with the present design.

FIG. 30 is a bottom view of the third insert of the salad shaker bowl of FIG. 1, in accordance with the present design.

FIG. 31 is a perspective view of an assembly of the bowl of the salad shaker bowl of FIG. 1 and the third insert, in accordance with the present design.

FIG. 32 is a top view of the assembly of the bowl of the salad shaker bowl of FIG. 1 and the third insert, in accordance with the present design.

FIG. 33 is a perspective view of the assembly of the bowl of the salad shaker bowl of FIG. 1 and the inverted first insert, in accordance with the present design.

FIG. 34 is a perspective view of the assembly of the bowl of the salad shaker bowl of FIG. 1 and the inverted second insert, in accordance with the present design; and, FIG. 35 is a perspective view of the assembly of the bowl of the salad shaker bowl of FIG. 1 and the inverted third insert, in accordance with the present design.
